ARTICLE RECEPTACLE

Charles E. Jones, Chicago, Ill., assignor to Commonwealth Plastics, Inc., Chicago, Ill., a corporation of Delaware

Application July 30, 1949, Serial No. 4,220

Term of patent 7 years

(Cl. D58—11)

To all whom it may concern:

Be it known that I, Charles E. Jones, a citizen of the United States, residing at Chicago, in the county of Cook and State of Illinois, have invented a new, original, and ornamental Design for an Article Receptacle, of which the following is a specification, reference being had to the accompanying drawing, forming part thereof.

Fig. 1 is a front perspective view of an article receptacle showing my new design.

Fig. 2 is a rear perspective view thereof, and Fig. 3 is a cross-sectional view taken on the line 3—3 of Fig. 1.

I claim:

The ornamental design for an article receptacle, substantially as shown.

CHAS. E. JONES.
